UNITED STATES PATENT OFFICE

OSCAR F. GORANSSON, OF SPRINGFIELD, MASSACHUSETTS

ANCHORING DEVICE

Application filed October 21, 1930. Serial No. 490,142.

This invention relates to improvements in anchoring devices and is directed more particularly to devices for anchoring objects such as marking plates to a roadway or the like.

5 The principal object of the invention is directed to the provision of an anchoring device which is so arranged and adapted that it may be driven into the ground and then expanded in its position in the ground so as to 10 make it difficult, if not impossible, to pull the device from its anchorage.

In the preferred form of the invention the device will be described in connection with the anchoring of marking plates or the like

15 to the roadway, but it will be understood that the novel features of the invention are applicable for anchoring devices in general.

The well-known circular marking plate employed to mark off areas of the ground, 20 that is, safety zones, cross walks and the like, in roadways, are usually anchored in place by bolts or the like, but they soon become loose so as to be displaced from their position. The anchoring device of this invention 25 is adapted to hold the said markers in place and prevent if not make it impossible for the markers to be removed accidentally or otherwise.

According to the novel features of the invention, the device includes an expandable bolt member which may be driven into the roadway and which may then be expanded by means operating internally thereof. The device is simple in construction so as to be 30 economical to manufacture and is readily usable so that it may be easily installed.

Various novel features and advantages of the invention will be hereinafter more fully referred to in connection with the following disclosure which describes the embodiment 40 of the invention at present preferred.

For purposes of disclosure the invention is described in the accompanying drawing, wherein

45 Fig. 1 is a side elevational view of the anchoring device of the invention, showing how it is inserted in the ground for anchoring a marking plate.

50 Fig. 2 is a sectional view on the line 2—2 of Fig. 1, and

Fig. 3 is a modified form of certain parts of the invention.

Referring to the drawing more in detail the invention will now be described.

In Fig. 1, I have shown in section a marker 2 commonly termed a marking plate which it is usual to locate on a roadway or the like. A plurality of such plates are located in spaced relation for marking off certain areas of the roadway, such as cross walks, safety zones or the like. This plate 2 may take any form desired, but as a common form is circular in shape and has a central opening 4 therethrough.

An expandable anchor bolt 6 is provided which is pointed at its lower end as at 8 and has a head or flange 10 at its upper end for setting in a recess 12 of the plate 2. This bolt on its outer side is provided with alternate grooves 14 and ridges 15, so as to provide a roughened corrugated surface. Instead of the grooves and ridges shown the outer surface of the bolt may be otherwise roughened so as to tend to prevent the withdrawal of the bolt after it has been driven into the ground. The interior of the bolt is hollowed out or is provided with a bore which is of a tapering nature. That is, the bore is larger at the upper end of the bolt than it is at the lower end thereof.

According to the preferred form of the invention, the bore is made to have straight-sided or non-tapering cylindrical portions 16, 17, 18 and 19. These from the upper side of the bolt downwardly are of decreasing diameter, as shown, and the straight-sided portions are connected by tapering portions. As will be seen, the straight-sided portion 16 of the bore at the upper end of the bolt is somewhat larger in diameter than the straight-sided portion 19 at the lower end. Grooves 20 are provided in the sides and through the walls of the bolt which open into the bore. As in Fig. 2, the grooves form wall sections 21 tied together at the upper and lower side of the bolt.

A wedge member 19 preferably in the form of a ball is provided which is adapted to be inserted in the bore of the anchor bolt. A cap 23 is provided which has a shank portion

24 and a head portion 26, the shank portion 24 of which is arranged to fit in the upper end of the bore so that the flange or head 26 may rest on the upper end of the bolt.

- 5 In operation the bolt 6, as in Fig. 1, is inserted through the opening in the plate 2 and is then pressed or driven into the roadway or ground at a point where it is desired to locate the plate 2. With the plate 2 resting 10 on the roadway and with the bolt inserted in the roadway so that its head bears in the recess of the plate 2, the wedge ball 19 is inserted in the upper end of the bore of the bolt. The ball wedge is then driven downwardly in the bore of the bolt by means of any 15 suitable tool. As it is driven downwardly into the gradually tapering bore, the sides 21 of the bolt are expanded, the slots 20 therein making this possible.
- 20 The ball 23 may be forced in the bore of the bolt to various depths depending more or less on the relative size of the ball and bore and upon the ability of the bolt to expand. As the bolt is expanded by the ball its walls 25 of course assume a more or less expanded position represented by dot-dash lines in Fig. 1. When the bolt is expanded to the desired or required degree, the cap 23 is placed thereon so that its hub 24 is inserted 30 in the bore and in this way the bore of the bolt is closed and the upper side of the cap 23 is more or less flush with the surface of the plate 2. The expanding of the bolt serves 35 to securely anchor the bolt in the roadway and thereby anchor the plate in place.

The tapering walls between the straight-sided portions of the bore facilitate the ball being driven downwardly of the bore and when the ball enters the straight-sided or 40 non-tapering portions of the bore below the top end of the bolt so as to expand the walls, the non-tapering walls of the bore tend to converge slightly upwardly and inwardly so as to lock the ball against an upward movement. At least the straight walls of the bore 45 tend to form a restricted opening at their upper ends to prevent the ball from moving upwardly within the bore, which is of course desired.

50 In this way, as the ball is driven downwardly of the bore of the bolt, it not only expands the bolt but is locked in place. By expanding the bolt it is of course anchored securely in place and therefore holds the plate 2 against displacement.

According to the modification of the invention in Fig. 3, I provide a combined cap and wedge indicated generally by 30. This 60 includes an upper cap portion 32 for resting on the upper end of the bolt and a hub portion 34 for fitting in the upper end of the bore as well as a depending portion 36 on the lower end of which is carried an enlarged wedge portion 38. With this form of the invention, the member 36 is inserted in the

bore of the bolt 6 and is driven downwardly so that the expanding portion 38 will expand the bolt while the flange 32 comes to rest on the upper side of the bolt.

This member 30 is locked against upward 70 movement in the bore of the bolt by the straight-sided or non-tapering portions of the bore which tend to converge inwardly and upwardly when the sides of the bolt are expanded by the enlarged end 38. As in the 75 former case the bolt is expanded to the desired degree by the wedge member 30 which is locked in place with the bolt in its expanded position.

The anchoring device may be modified or 80 changed to adapt the apparatus for other uses than that described. It has been found to be adequate to hold the said marking plate securely in place, it is simple in construction 85 so as to be readily usable and is efficient in its operation.

Having described the invention in the form at present preferred, what I now desire to claim and secure by Letters Patent of the 90 United States is:

1. The combination of a marking plate for a roadway or the like provided with a central opening therethrough and a recess therearound in the upper face thereof with an anchoring device for securing said plate to a roadway comprising in combination, a bolt having a unitary body portion for extending downwardly through the opening in the plate and adapted to be driven into a roadway, a head on said bolt receivable in 100 said recess, the said bolt being pointed at its lower end and provided with a continuous stepped axial bore extending downwardly from the upper side thereof and terminating adjacent the lower pointed end, the 105 said bore having alternate connected straight and tapering portions and the said straight portions decreasing successively in diameter downwardly from the upper end of the bore, the said body portion having longitudinally spaced corrugations on its outer side and being provided with spaced longitudinal slots in its sides opening into said bore and terminating at a distance from the lower and upper ends thereof, a wedge member having 110 a curved surface and adapted to slip through the uppermost straight portion of the bore and being of greater size than successive portions of the bore so that it may be driven downwardly in said bore into a certain straight portion thereof to expand the sides of the body between its opposite ends, whereby the body is bulged between its ends to cause the said certain straight portion of the bore to contract above said wedge member 115 and lock the same in said certain straight portion.

2. The combination of a marking plate for a roadway or the like provided with a central opening therethrough and a recess 120

therearound in the upper face thereof with an anchoring device for securing said plate to a roadway comprising in combination, a bolt having a unitary body portion for extending downwardly through the opening in the plate and adapted to be driven into a roadway, a head on said bolt receivable in said recess, the said bolt being pointed at its lower end and provided with a continuous stepped axial bore extending downwardly from the upper side thereof and terminating adjacent the lower pointed end, the said bore having alternate connected straight and tapering portions and the said straight portions decreasing successively in diameter downwardly from the upper end of the bore, the said body portion having longitudinally spaced corrugations on its outer side and being provided with spaced longitudinal slots 20 in its sides opening into said bore and terminating at a distance from the lower and upper ends thereof, a wedge member having a curved surface and adapted to slip through the uppermost straight portion of 25 the bore and being of greater size than successive portions of the bore so that it may be driven downwardly in said bore into a certain straight portion thereof to expand the sides of the body between its opposite 30 ends, whereby the body is bulged between its ends to cause the said certain straight portion of the bore to contract above said wedge member and lock the same in said certain straight portion, and a cap having a portion for inserting in the upper end of the bore and a part for overlying the upper end of the bolt receivable in the recess of said plate.

In testimony whereof I affix my signature.
40 OSCAR F. GORANSSON.
